UNITED STATES PATENT OFFICE

2,544,777

KNIFE SHARPENER

Joseph A. Cahil, New York, N. Y.

Application November 26, 1948, Serial No. 62,073

1 Claim. (Cl. 51—208)

1

The present invention relates to a new and improved knife sharpener, the construction of which permits the effective use thereof on any desired surface.

Heretofore, difficulty has been encountered in holding hand knife sharpeners for effective operation. If the sharpeners are not properly held while the knife is drawn across the sharpening elements, the sharpening action afforded by these prior devices is impaired.

It is an object of the present invention to provide a new and improved knife sharpener adapted to be held upon any suitable surface to accomplish the sharpening operation effectively.

This object, as well as others which will appear from the following detailed description, is attained by a knife sharpener comprising sharpening mechanism enclosed within a case having a centrally disposed notch to permit access thereto. A handle extends from the case, the free end thereof being in the same plane as the under surface of the case to provide an effective bearing area when the sharpener is grasped during use.

The invention may be better understood from the following detailed description, taken in conjunction with the accompanying drawings, in which:

Figure 1 is a plan view of a knife sharpener constructed in accordance with the present invention;

Figure 2 is a view in end elevation of the device of Figure 1;

Figure 3 is a view in cross section of the device, taken at line 3—3 of Figure 1 and looking in the direction of the arrows; and

Figure 4 is a plan view partly broken away and in section, taken at line 4—4 of Figure 2 and looking in the direction of the arrows, showing the structural details of the device.

Referring now to the drawings, the knife sharpener comprises a sharpening mechanism 10 enclosed within a case 11 formed of any suitable material, such as a plastic of the phenol-formaldehyde class, for example. To facilitate assembly, case 11 may be formed as two separate units, a base plate 12 and a body member 13. Body member 13 is provided with a centrally disposed V-shaped notch 14 having an aperture 15 therein for permitting access to the sharpening mechanism 10. A handle 16, preferably an integral part of body member 13, extends therefrom and is formed at its free end 17 with a bearing pad 18 positioned in the plane of the under surface of base plate 12.

Sharpening mechanism 10 comprises a series 55

2

of abrasive or cutting rollers 19 mounted on angular flanges 20 and 21 extending from side walls 22 and bottom wall 23, respectively, of a frame 24. Rollers 19 are journaled in the flanges 20 and 21 by means of pintles 25. Frame 24 is secured to body member 13 by screws 26 or other suitable fastening means.

When the device is assembled, the body member 13 is secured, as by glueing, to base plate 12, 10 a flange 12a serving to locate and position the body member 13 in the position illustrated in Figures 1 and 3.

In operation, the sharpening device is held upon any supporting surface with the bottom plate 12 and bearing pad 18 resting upon the surface. The user grasps the handle 16 with one hand and inserts a knife blade into notch 14 for contact with the rollers 19 of the sharpening mechanism. The device is thus firmly held in 20 proper position while the blade is moved across the rollers 19, to form an effective cutting edge.

From the foregoing, it is apparent that the invention provides a new and improved knife sharpener formed to enable the sharpener to be firmly held in a desired position while the device is being used.

While the invention has been described with specific reference to the structure shown in the accompanying drawings, it is not to be limited 30 save as defined in the appended claim.

I claim:

A knife sharpener having stabilization against angular movement in both horizontal and vertical planes comprising, in combination, a housing 35 having side, end and top and bottom members, said bottom member having a bearing surface contained in a given plane and adapted to rest squarely upon a supporting surface, a handle rigidly secured to said housing and extending 40 laterally outwardly therefrom spaced from the plane of the bottom member to afford a finger-receiving opening between the handle and the supporting surface, a depending foot portion on said handle spaced from said housing, said foot 45 being formed on its free end with a bearing surface disposed in the plane of the said bottom member, said foot and said bottom member affording stabilization of the knife sharpener against turning movement in the plane normal to the supporting surface while the sharpener is pressed against a supporting surface by downward thrust between the supporting foot and the housing, said foot providing in addition frictional drag opposing angular movement of said sharpener in the plane parallel to the supporting sur-

face, an elongated notch in said top member for receiving the knife blade and sharpening mechanism comprising means for engaging the knife-edge at points spaced lengthwise of the blade, said sharpening mechanism being maintained in substantially fixed orientation relative to the supporting surface during the course of operation.
